UNITED STATES PATENT OFFICE.

WILLIAM BERTIE FIFE, OF WALLASEY VILLAGE, ENGLAND.

EDGE-TOOL.

1,282,404.

Specification of Letters Patent. Patented Oct. 22, 1918.

Application filed April 5, 1918. Serial No. 226,855.

To all whom it may concern:

Be it known that I, WILLIAM BERTIE FIFE, a subject of the King of Great Britain, residing at Wallasey village, in the county of Chester and Kingdom of England, have invented certain new and useful Improvements in Edge-Tools, of which the following is a specification.

This invention relates to edge tools of the kind having a blade provided with a knife edge and a serrated or saw edge, and the object of the invention is to provide such tools with a handle which can be converted from a handle of the haft type to a handle of the type suitable for operating a saw, and vice versa.

According to this invention the handle, having the appearance of an ordinary knife handle or haft handle, is formed of two parts, longitudinally divided, one part being secured to the saw-knife blade and the other part hinged to this fixed part at the outer ends of the same. The hinged or movable part can be turned about this hinge into an inclined position, having the appearance of a handle of the type suitable for operating a saw, and is secured in this position by a strut or connecting piece formed of two links joined together and pivoted at the ends to the inner ends of the movable and the fixed parts, the joint being locked by an extension on one link provided with a pin adapted to engage a hole or holes in the other link. When the parts are brought together, having the appearance of an ordinary knife handle, the folded links engage or fit into recesses formed in the movable and fixed parts, the parts being locked in this position by a spring catch or other suitable means. The central portion of the movable part is rounded off in cross section and a corresponding recess is formed in the fixed part to receive the contact portion of the same.

In the accompanying drawings:—

Figure 1 is a side elevation, Fig. 2 a plan view, and Fig. 3 a cross-section of the tool showing the handle converted into a handle of the haft type;

Fig. 4 is a side elevation of the handle portion of the tool converted into a handle of the kind suitable for operating a saw, and Fig. 5 is a similar view in longitudinal section in the partially opened position;

Fig. 6 is a plan view of Figs. 4 and 5, but showing the strut or connecting links re-

moved and the movable part of the handle turned back into a horizontal position;

Fig. 7 is a separate view on a larger scale of such portions of the connecting links as are necessary to illustrate the locking arrangement securing the links in alinement and Fig. 8 is a longitudinal section of the same.

Referring to the drawings, which represent a preferred construction of a saw-knife made according to this invention, 2 represents the blade of the saw-knife which is provided with a knife-edge 3 and a serrated or saw-edge 4. The handle of the saw-knife is composed of two longitudinal parts, the part 5 being secured to the blade 2 and the part 6 hinged at 7 to the fixed part 5. When closed, as shown in Figs. 1, 2 and 3, these parts form the ordinary handle of the saw-knife when used as a knife; but when separated from each other, as shown in Fig. 4, into a saw-like handle, the movable part 6 forms the handle. The movable or turnable part 6 is secured in the raised or inclined position or the more or less vertical position by a strut 8, Figs. 4, 7 and 8, jointed at the center 9 and pivoted at the inner ends of the parts 5 and 6, the said strut comprising a single link 10 jointed at 9 to and between two links 12 and 12. The single link 10 has an extension 13. The links are locked together in alinement by means of a stud 14, made of hardened steel, secured in the extension 13 and provided with rounded or spherical ends which project from the sides of the extension. The rounded or spherical ends of the stud 14 engage, when the links are forced into alinement, with corresponding recesses in the inner sides of the links 12 between which the extension 13 works. A limiting stop 15 is provided in one of the links 12 which engages with the end of the extension 13 and thereby facilitates the location of the stud 14 ends and the corresponding recesses. The parts of the handle are locked together in the closed position by means of the extension 13 engaging with a flat spring 16 fixed in a recess formed in the fixed part 5.

The handle of the saw-knife may be made of any suitable material such as metal, wood, or papier-mâché. The teeth of the blade may be formed in the opposite direction to that shown in the drawings, in which case the sawing action is done by a pull-stroke instead of by a push-stroke.

I declare that what I claim is:—

1. An edge tool having a blade provided with a knife edge and a serrated or saw edge, a handle carried by the blade, and having a movable portion adapted to form the saw handle.
2. An edge tool having a blade provided with a knife edge and a serrated or saw edge, a handle carried by the blade, and having a pivoted portion adapted to form the saw handle.
3. A saw-knife having a handle formed of two longitudinal parts hinged together at their outer ends, one part being fixed at its inner end to the blade of the saw-knife and the other part adapted to be raised or turned into an inclined or more or less vertical position, and means for locking the movable part in such a position, substantially as described.
4. In a saw knife, the combination with the blade, of a handle formed of two longitudinal parts, one part being fixed at its outer end to the blade, and the other part hinged to the fixed part, so that it can be raised, and a jointed strut coupled at one end to the fixed part and at the other end to the hinged part for locking the hinged part in a raised position when the two parts of the strut are in alinement.
5. In a saw knife, the combination with the blade, of a handle formed of two longitudinal parts, one of which is fixed to the blade and the other part hinged to the fixed part and having recesses in their abutting faces, and a jointed strut coupled on oppo-

site ends to the fixed part and hinged part respectively, and so arranged as to fold or fit into recesses in the folded and fixed parts when the two parts of the handle are closed together, or to be extended and locked in alinement when the hinged part is turned into the raised position.

6. In a saw knife, the combination with the blade, of a handle formed of two longitudinal parts, one of which is fixed to the blade and the other part hinged to the fixed part and having recesses in their abutting faces, a jointed strut coupled at opposite ends to the fixed part and the hinged part respectively, an extension member projecting from one of the parts of the strut at the joint and adapted to limit the outward movement of the same, and a spring fixed in the recess in the fixed part of the handle for locking the two parts of the handle in the closed position.

7. An edge tool having a blade provided with a knife edge and a saw edge, a handle rigidly secured to the blade, and a movable member carried by the handle and adapted to be moved in a position at an angle thereto to form a handle when used as a saw.

In witness whereof, I have hereunto signed my name, in the presence of two subscribing witnesses.

WILLIAM BERTIE FIFE.
